UNITED STATES PATENT OFFICE.

HUGO NEUMAN, OF DETROIT, MICHIGAN.

WINDSHIELD TUBING.

Application filed February 21, 1921. Serial No. 446,721.

To all whom it may concern:

Be it known that I, HUGO NEUMAN, a citizen of the United States of America, residing at Detroit, in the county of Wayne and State of Michigan, have invented certain new and useful Improvements in Windshield Tubing, of which the following is a specification, reference being had therein to the accompanying drawings.

The invention relates to tubing which is used for the formation of channel frames and is particularly applicable to wind shields. The invention has for its object the provision of tubing formed of a channel member and a surrounding outer tube having seamed edges, the seams being at the outer edges of the sides of the channel member and within the tubing. With this arrangement, the seams strongly reinforce the tubing and are concealed so that the exposed surface of the outer tube is uninterrupted. With this object in view, the invention resides in the novel features of construction as more fully hereinafter set forth.

In the drawings:

Figure 1 is a side elevation of a portion of tubing embodying my invention;

Figure 2 is a transverse cross section therethrough showing the glass in place;

Figures 3, 4 and 5 are views similar to Figure 2 showing modified constructions.

Fig. 6 is an enlarged cross-section of the frame showing the seam between the two metal members.

Heretofore channel tubing has been formed from flat strips which respectively form the channel member and the outer tubing having their edges seamed together either at the base of the channel member or outside the outer tube. With the first of these constructions, the seamed edges do not appreciably reinforce the tubing, while with the latter construction the seams are exposed to view, are not protected from the weather and furthermore form cracks in the enamel coating upon the tubing. By means of my improved construction, the seams are concealed and being located at the outer edges of the sides of the channel member, they strongly reinforce the tube.

In detail and as shown in Figures 1 and 2, the channel tubing comprises the channel member 1 and the surrounding outer tube

2 having their edges 3 and 4 seamed together. The edges 3 are U-shaped and open toward the sides 5 of the outer tube and the bases 6 of the U's are substantially in the planes of the respective sides 7 of the U-shaped channel member. The edges 4 of the channel member are U-shaped and open outwardly to cooperate with the U-shaped edges 3 and be rigidly secured thereto. For the purpose of more rigidly securing these edges to each other, the U-shaped edges 4 are clamped between the U-shaped edges 3 and the sides 5 of the outer tube.

From the above description it will be readily seen that the seams between the channel member 1 and the outer tube 2 form reinforcements for the tubing, and are located within the tubing so that the exposed surface of the outer tube is un-interrupted; and furthermore, the seams open into the space within the tubing so that when the glass 8 is in place within the channel member, the seams are concealed from view as well as from the weather.

In the modified constructions shown in Figures 3, 4 and 5, the cross sectional contour of the outer tubes are varied, but in each case there is the same arrangement of the seams at the outer edges of the sides of the channel member and extending within the space inclosed by the channel member and the outer tube.

What I claim as my invention is:

1. A device of the class described comprising a channel member adapted to receive an edge of a transparent member, the edges of said channel member extending inwardly, and a tube enclosing the channel member and having inwardly extending portions return-bent around the inwardly extending edges of said channel member.

2. A device of the class described comprising a channel member adapted to receive an edge of a transparent member, said channel member having U-shaped portions at its outer edges, and a tube enclosing said channel member and having return-bent portions abutting opposite sides of the transparent member and interlocking with the U-shaped portions of said channel member.

In testimony whereof I affix my signature.

HUGO NEUMAN.
